HAND STAMP

Frank R. Anderson, Santa Maria, Calif., assignor to Westates Space-Era Products, Inc., Los Angeles,
Calif., a corporation of California

Filed Mar. 8, 1967, Ser. No. 6,115

Term of patent 14 years

(Cl. D64—10)

FIG. 1 is an isometric view of a hand stamp showing my new design thereof.

FIG. 2 is a left side elevational view thereof.

FIG. 3 is a rear elevational view thereof.

FIG. 4 is a front elevational view thereof.

FIG. 5 is a top plan view thereof.

FIG. 6 is a bottom plan view thereof.

FIG. 7 is a left side elevational view showing the stamp in the actuated position.

The essential features of the design reside in the portions shown in solid lines, conventional printed indicia being shown in broken lines in FIG. 6.

I claim:

The ornamental design for a hand stamp, substantially as shown and described.
